UNITED STATES PATENT OFFICE

150,916

DESIGN FOR A BEVERAGE DISPENSING MACHINE

Leslie Arnett, Chicago, Ill., assignor to Square
Manufacturing Company, a corporation of Illi-
nois

Application August 5, 1946, Serial No. 132,388

Term of patent 14 years

(Cl. D52—3)

To all whom it may concern:

Be it known that I, Leslie Arnett, a citizen of the United States, residing at Chicago, in the county of Cook and State of Illinois, have invented a new, original, and ornamental Design for a Beverage Dispensing Machine, of which the following is a specification, reference being had to the accompanying drawings, forming a part thereof, in which:

Figure 1 is a front elevational view of a beverage dispensing machine, showing my new design;

Figure 2 is a side elevational view of the machine, looking from the right of Figure 1;

Figure 3 is a plan view of the machine;

Figure 4 is a rear elevational view of the machine;

Figure 5 is a side elevational view of the ma-
chine, looking from the left of Figure 1; and
Figure 6 is a bottom view of the machine.

I claim.

The ornamental design for a beverage dis-
pensing machine, as shown.

LESLIE ARNETT.
